SUCTION-VAPOR HEATING SYSTEM

William M. Smith, Chicago, Ill., assignor to Vapor Car Heating Company, Inc., Chicago, Ill., a corporation of New York

Application July 26, 1939, Serial No. 286,544

1 Claim. (Cl. 237—6)

This invention relates to certain new and useful improvements in a steam heating system, more particularly a system of the so-called vapor type in which steam at substantially atmospheric pressure is circulated through the radiating units.

According to this invention an aspirator or exhaustor is provided in the steam supply pipe through which aspirator the steam first introduced to this system under an initial pressure is passed under increased velocity to create a suction which serves to draw fluids from the radiating units and lower the pressure therein and thus draw low-pressure steam from the supply-pipe beyond the aspirator into and through the respective radiating units.

The principal object of this invention is to provide an improved heating system of the type briefly described hereinabove and disclosed more in detail in the specifications which follow.

Another object is to provide improved means for circulating low-pressure steam.

Another object is to provide improved means for heating a plurality of separate spaces or compartments, especially in a railway car.

Other objects and advantages of this invention will be more apparent from the following detailed description of certain forms of apparatus constructed and operating according to the principles of this invention.

In the accompanying drawing:

Fig. 1 is a diagrammatic layout of the heating system.

Fig. 2 is a central vertical section through the exhaustor unit.

Fig. 3 is a view similar to Fig. 2 showing a modification.

Referring first to Fig. 1, the improved heating system comprises in general the main source of steam supply A, the vapor regulator B, the several radiating units C, C' and C'' provided with the respective control valves D, D' and D'', the aspirator or exhaustor E, and the piping connecting these several elements as hereinafter described.

The steam source A is indicated as a main pipe extending from the steam generator (not shown). For example, when the system is used on a railway car (for which use this system is particularly designed), the pipe A will be the main steam pipe which extends throughout the length of the train, from car to car, and usually receives its steam from the locomotive. A pipe 1 leads from train-pipe A to the inlet chamber 2 of vapor-regulator B. If the steam in pipe A

is under too great a pressure, a pressure reducing valve 3 may be positioned in the pipe 1.

The vapor-regulator B may be of any suitable type, the well-known form here shown by way of example comprising the inlet chamber 2 and outlet chamber 4 connected by port 5 which may be closed by the movable valve member 6. Valve 6 is connected through the link and lever system 7, 8 and 9 with the expansible thermostatic element 10. When thermostatic element 10 is surrounded by steam or subjected to a steam temperature, it will expand and close the valve 6. When the temperature in chamber 11 surrounding the thermostatic element 10 falls below steam temperature, the thermostatic element will contract and valve 6 will open to permit steam from the source A to flow through pipe 1, inlet chamber 2, port 5, outlet chamber 4, and pipe 12 to and through the exhaustor E and thence through the pipe 13 into the chamber 14 of the regulator which is connected through outer and inner passages 15 and 16 with the atmosphere. The pipe loop comprising pipes 12 and 13 serves simultaneously as a supply and drain pipe. Condensate which drains back through pipes 12 and 13 will, for the most part, drain out through the outer passage 15, whereas non-condensable gases and steam will flow out through inner passage 16 and chamber 11 in contact with thermostatic element 10. Whenever an excess of steam is supplied to the pipe-loop, this steam will flow into chamber 11 in contact with the thermostatic element 10 whereupon the thermostat will expand and close valve 6 thus temporarily shutting off the steam supply. When the steam in chamber 11 condenses and disc 10 cools the valve will automatically open. In this manner the pipe loop 12, 13 will be automatically kept full of steam or vapor at substantially atmospheric pressure, since the discharge end of the loop is open to the atmosphere.

The system as thus far described (except for the exhaustor E) is substantially the same as the ordinary vapor heating system in which the pipe loop here indicated at 12, 13 is utilized as a radiator. In the present system, although the loop may be utilized to radiate heat, its primary purpose is to function as a supply-pipe from which vapor or low pressure steam is distributed to the several radiating units C, C' and C''. The supply-pipe 13 need only be long enough to provide convenient places for attaching the inlet ends of the several feed-pipes 17, 17' and 17'' which lead to the respective radiating units. It will be noted that (in the present example) all

of the feed-pipes connect in pipe 13 at locations beyond or at the downstream side of exhauster E so that all of the steam flowing to the radiating systems must first pass through the exhauster or aspirator E, which in the example here shown is located near the end of pipe 12.

The condensate and other fluids discharged from the several radiators flow out through the respective return pipes 18, 18' and 18'' all leading into the common return pipe 19 which discharges into the aspirator or exhauster E as hereinafter described.

Suitable inlet or cut-off valves D, D' and D'' are positioned in the respective feed-pipes in advance of the several radiating units. The radiators C, C' and C'' may be of any desired type but are here shown as comprising an inner feed-pipe 20 through which the steam admitted through valve D flows to the opposite end of the radiator into cap 21 and then back together with condensate through the outer pipe 22 in which inner pipe 20 is centered. The other end of outer pipe 22 discharges through steam-trap 23 into the return pipe 18. The outer pipe 22 is preferably provided with a plurality of spaced fins 48 to increase the heat transfer surface. The valves D and D' are here indicated as ordinary hand-operated cut-off valves, although any or all of these valves may be electrically operated valves of the form indicated at D'' in connection with radiator C. This valve D'' is of a type which automatically closes but which is opened when an energizing circuit flows as follows: from the battery 24 or other source of power through wires 25 and 26, valve D'', wire 27, switch 28, and wires 29 and 30 back to the battery. The switch 28 will be closed as long as relay coil 31 is energized over the following circuit: from battery 24 through wire 25, resistance 32, coil 31, resistance 33, and wire 30 back to the battery. The valve D'' will thus be open as long as the temperature in the compartment or space heated by unit C'' is below the desired temperature. When this temperature is reached, a circuit will be closed through the thermostat 34 suitably located in the compartment, this circuit being as follows: from one terminal of relay coil 31 through wire 35, thermostat 34, and wire 36 back to the other terminal of the coil. This will short circuit the relay coil so that switch 28 may be automatically opened by spring 37. The valve D'' will now automatically close. Each of the several inlet valves may be separately and thermostatically controlled in the manner just indicated, or by any other suitable means. It may here be stated that while three radiating units have been shown by way of example, there may be any reasonable number of these radiators all supplied with vapor from the same supply-pipe 13, and each radiating unit may be separately controlled. This system is especially suitable for heating the several compartments of a railway passenger car.

The exhauster or aspirator E (see Fig. 2) comprises a closed substantially tubular casing into the inlet end of which is connected the delivery pipe 12 leading from the vapor regulator, and from the discharge end of which leads the supply-pipe 13. Within this casing is formed a suitable web 38 so as to provide a restricted Venturi passage 39 through which the steam flows at increased velocity into the main aspirator chamber 40 and thus out through pipe 13. The return pipe 19 leads into chamber 40 ad-

5 jacent the Venturi passage, and the suction or partial vacuum created by this venturi in well known manner will draw fluids from pipe 19 into the chamber 40, these fluids being then carried along with the steam into and through pipe 13. It is to be understood that in this description and in the claim which follows the term "aspirator" is intended to cover any exhausting device of this venturi or ejector type whereby the flow of steam under its initial pressure serves to suck the fluids in from the return pipe and thus create a circulation through the several radiating units.

In general operation, the vapor regulator B will function to keep the supply pipe 12, 13 full 15 of steam, as well as all of the radiating units that are in service, that is those units having the inlet valves D open. Whenever an excess of steam tends to force steam through the discharge portion of the vapor regulator, the thermostatic element 10 will automatically close valve 6 and temporarily stop the initial steam supply. All of this steam is originally delivered through pipe 12 and through the Venturi portion of the aspirator under a substantial pressure, but the steam pressure in supply-pipe 13 and in the radiating units falls to substantially atmospheric pressure since the system is open to the atmosphere at the discharge end. Therefore only low-pressure steam is delivered through feed-pipes 17 to the radiating units, but a substantially lower pressure is created in return pipes 18 and 19 by the suction of aspirator E so that a steam flow will be induced through each of the radiating units. The fluids returned 30 from the radiating units through pipe 19, consisting of condensate, non-condensable gases and some steam will flow back into and through the supply-pipe 13 along with the fresh steam which creates the suction. The condensate will 35 eventually drain out of the system through the vapor regulator, all of the piping being suitably inclined to facilitate this drainage.

Fig. 3 indicates a combined aspirator and supply valve suitable for use when only one 40 radiating unit is to be supplied, or where a single valve may simultaneously control the supply of steam to all of the radiating units. This aspirator E' is, as before, provided with a Venturi passage 39 and the return pipe 19 discharges 45 into the chamber 40 adjacent this venturi. The feed-pipe 17, instead of leading from supply-pipe 13, leads from a feed chamber 41 formed above the discharge end of chamber 40 and connected therewith through a port 42 controlled 50 by valve 43. This valve 43 may be of the type hereinabove described as D'' and may be controlled thermostatically in the same manner. Chamber 41 is also connected through the drain port 44 with aspirator chamber 40, port 44 normally being closed by valve member 45 carried by the thermostatic bellows 46 mounted on adjusting screw 47. As long as chamber 40 is filled with steam, the bellows 46 will expand 55 so as to hold valve 45 in position to close port 44. Any condensate flowing back through feed-pipe 17 will flow out through the main port 42 as long as the inlet valve 43 is open. However, when valve 43 closes this condensate will be 60 pocketed in the chamber 41. However, whenever the main steam supply is cut off the thermostatic member 46 will contract and open the drain port 44 so as to permit any condensate trapped in chamber 41 to drain out. Of course the greater portion of the condensate will always 65 drain out or be sucked out through return pipe 70 75

19 into the aspirator chamber and then will flow out through pipe 13.

The steam traps 23 serve to prevent the continued flow of steam thereby in either direction. Thus they not only tend to prevent wasteful circulation of steam when the radiator is filled but also prevent a reversal of the direction of steam flow when condensation creates a vacuum in the radiator, and when the main valve 6 of the vapor-regulator is closed, and the aspirator E is ineffective to create a suction on the return pipes 18.

I claim:

In combination with a radiating unit, and feed and return pipes leading thereto and therefrom an aspirator comprising a Venturi passage and a chamber beyond the venturi, supply and discharge pipes connected to the respective ends

5 of the aspirator for delivering a flow of steam through the Venturi passage and chamber, the return pipe discharging into the aspirator chamber adjacent the venturi, a feed-chamber positioned above the discharge end portion of the aspirator and connected with the aspirator chamber through a steam port, a cut-off valve controlling the port, the feed-pipe leading from the feed chamber, a drain port between the feed chamber and the aspirator chamber, a thermostatic element positioned within the aspirator chamber in the path of the steam flow, and a valve member carried by the thermostatic element and closing the drain port when the thermostatic element is expanded in the presence of steam.

WILLIAM M. SMITH.
